UNITED STATES PATENT OFFICE.

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY.

REVERSIBLE-FULCRUM MECHANISM.

1,425,650.

Specification of Letters Patent. Patented Aug. 15, 1922.

Application filed August 8, 1921. Serial No. 490,499.

To all whom it may concern:

Be it known that I, WILLIAM C. HEDGCOCK, a citizen of the United States, residing at Chicago, in the county of Cook and State of Illinois, have invented certain new and useful Improvements in Reversible-Fulcrum Mechanism, of which the following is a specification.

This invention relates to a new and improved reversible fulcrum mechanism and to the co-operation of such mechanism with a brake beam. This application relates to a modification of the construction shown in my co-pending application, Serial No. 459,790, filed April 8, 1921.

It is an object of the present invention to provide a one-piece reversible fulcrum which is simple and durable in construction, efficient in operation and which is adapted to meet all requirements for successful commercial use. It is another object to provide a simple and efficient locking connection between such a fulcrum and the compression member of a truss brake beam. Other and further objects will appear as the description proceeds.

Broadly, my invention comprises an integrally formed reversible fulcrum having portions embracing a brake beam compression member, these portions being so formed as to engage the brake beam member to limit rotation of the fulcrum about its axis and to stop such rotation at proper points for operation of the fulcrum. A locking member is provided adapted to maintain the fulcrum located at one or the other of the limits of its movement about its axis. These positions are the operative positions and constitute a right or left hand fulcrum according to the position.

I have illustrated a preferred embodiment of my invention in the accompanying drawings in which—

Figure 1 is a plan view showing my fulcrum applied to a truss brake beam.

Figure 2 is a fragmentary view showing the end of the fulcrum fitted to the compression member of the brake beam.

Figure 3 is a view of Figure 2 as seen from the right.

Figure 4 is a view of Figure 2 as seen from above.

Figure 5 is a face view of the wedge locking member, and

Figure 6 is a view of Figure 5 as seen from above.

Referring now to Figure 1 of the drawings, the truss type of brake beam comprises the compression member 7 and the tension member 8, between which my improved fulcrum 9 is mounted. The ends of the tension member 8 are secured adjacent the ends of the compression member 7 and at these points are secured the members 10 adapted to receive the brake shoes. The fulcrum 9 is provided with a band portion 11 which surrounds or embraces the compression member 7. The upper and lower portions of the band 11 are provided with the V-shaped walls 12 and 13. The walls 13, as shown in Figure 2, engage the upper and lower surfaces of the compression member 7 and thus serve to limit the movement of the fulcrum about its own axis. As shown, the rear wall of the band 11 is provided with a rivet 14 which passes through the wall of the member 7 and which serves as a pivot about which the fulcrum may be rotated. When the fulcrum is rotated in the clockwise direction as seen in Figure 2, the walls 12 will engage the upper and lower surfaces of the compression member 7 and will limit this rotary movement. In one position of the fulcrum the brake beam is what is known as a right hand beam and in the other limiting position of the fulcrum the brake beam becomes the left hand beam.

The locking member 15, shown in Figures 5 and 6, is provided for the purpose of maintaining the fulcrum locked in either operative position. This member 15 comprises a flat body portion provided with lateral flanges 16 of even height throughout their length, and provided upon its opposite face with the wedge flanges 17. The member 15 is further provided upon the upper and lower faces of its edge with the hooks 18. The smaller end of the wedge is provided with the locking tongues 19. Two tongues 19 are provided so that the wedge will still be serviceable after one tongue may have been broken off by bending in use.

As best shown in Figures 2, 3 and 4, the wedge member 15 is inserted between the brake beam compression member 7 and the inner face of the fulcrum band 11. The flanges 16 engage the inner surfaces of the upper and lower flanges of the compression member 7 and thus prevent lateral movement of the wedge member 15 relative to the compression member.

As shown in Figure 4, the wedge flanges 17

engage co-operating wedgeways 20 upon the inner surface of the fulcrum. One of the hooks 18, as shown in Figure 2, engages the V-shaped wall 13 and overhangs that wall 5 to prevent rotation of the fulcrum about its axis.

As shown in Figure 4, the tongue 19 is bent laterally to lock the wedge in place.

If it is desired to change the brake beam 10 from left to right hand, or vice versa, it is only necessary to bend back the tongue 19, to knock out the wedge member 15, rotate the fulcrum, and then to re-insert the wedge member and again bend out the tongue.

15 The front end of the fulcrum is provided with two fingers 21 which are shaped and spaced from each other in such manner as to prevent the displacement of the tension member 8 and further to permit the fulcrum 20 to be reversed without binding against the tension member.

By means of my construction the fulcrum may be locked in its different operative positions in a simple and efficient manner and the 25 fulcrum may be reversed with a minimum expenditure of time and labor.

It is my intention to cover all my applications of the invention falling within the spirit and scope of the following claims.

30 What I claim is:

1. An integrally formed reversible fulcrum having portions embracing a brake beam compression member, said portions being adapted to limit reverse movements of 35 the fulcrum with respect to the brake beam members, and positive locking means adapted to engage said embracing portions and the brake beam member to lock the fulcrum in operative position relative to the brake 40 beam member.

2. An integrally formed reversible fulcrum having portions embracing a brake beam compression member, said portions

being adapted to limit reverse movements of the fulcrum with respect to the brake beam members, and a member having hooks 45 engaging the embracing portions and flanges engaging the brake beam member to lock the fulcrum in operative position relative to the brake beam member. 50

3. An integrally formed reversible fulcrum having V-shaped wall portions for embracing a brake beam compression member and limiting reversible movements of the fulcrum with respect thereto, and means 55 co-operating with the compression member and the part of one of said V-shaped wall portions in contact with the compression member for locking the fulcrum in operative position relative to the brake beam 60 member.

4. An integrally formed reversible fulcrum having V-shaped wall portions for embracing a brake beam compression member and limiting reversible movements of the 65 fulcrum with respect thereto, and means co-operating with the compression member having a hook portion adapted to engage one of said V-shaped wall portions to lock the fulcrum in operative position relative to the 70 brake beam member.

5. An integrally formed reversible fulcrum having V-shaped wall portions for embracing a brake beam compression member and limiting reversible movements of the 75 fulcrum with respect thereto, and a wedge member insertible between the fulcrum and compression member, said wedge member having flanges engaging the compression member and having a hook portion adapted 80 to overhang one of said V-shaped wall portions to lock the fulcrum in operative position relative to the brake beam member.

Signed at Chicago, Illinois, this 2nd day of August, 1921.

WILLIAM C. HEDGCOCK.
